SLIDING BREECHBLOCK LOCKING MECHANISM FOR SELF-LOADING FIREARMS

Bernard Maillard, Geneva, Switzerland, assignor to Society "Brevets Aero-Mecaniques," S. A., Geneva, Switzerland, a society of Switzerland

Original application March 30, 1951, Serial No. 218,370, now Patent No. 2,756,640, dated July 31, 1956. Divided and this application June 27, 1955, Serial No. 518,307

Claims priority, application Luxemburg March 30, 1950

4 Claims. (Cl. 89—187)

The present invention relates to self-loading firearms (this term being meant to include both semi-automatic firearms which require a separate trigger-pull for every shot, and automatic firearms, which fire bursts, and also double action arms capable of working either in semi-automatic or in fully automatic fashion) in which the breech-block structure is held temporarily locked in bore closing or active position by a longitudinal sliding unit carrying the striker and capable, once said breech-block structure has reached said active position, of further moving toward the front to perform this temporary locking action and to fire the cartridge.

In a different kind of firearm, i. e. repeating firearms, it has been suggested to use a longitudinally split breech-block, the sections or elements of which, when the breech-block is in its home position, are laterally expanded, into engagement with abutment shoulders provided on the inner walls of the breech-case housing. In such known firearms, the two breech-block elements are pivotally connected to each other about an axis located in the plane of symmetry (normally vertical) of the unit formed by the barrel and the breech-case and the above mentioned abutment shoulders are parallel to this axis. It is very important to give the breech-block elements a longitudinal dimension as small as possible, because said elements support a very great longitudinal thrust every time a shot is fired and they are necessarily slightly oblique. Now, in the known firearms of this type the opening provided in the breech-case for ejection of the spent cartridge cases is located in one of the sides of said breech-case, that is to say in one of the walls of the breech-case housing where must be provided one of the above mentioned abutment shoulders. Therefore, since this opening must extend rearwardly behind the rear edge of the cartridge chamber and since the abutment shoulder is necessarily formed in the portion of the above mentioned breech-case wall extending at the rear of said opening, the longitudinal dimension of the breech-block elements is greater than the longitudinal length of said opening. This dimension has proved to be too great for modern weapons.

The object of my invention is to obviate this drawback.

For this purpose the two above mentioned openings are provided in walls transverse to the above mentioned longitudinal plane of symmetry of the breech-case, that is to say in the top and bottom walls, respectively of said breech-case. Thus the abutment shoulders can be located in portions of said breech-case intermediate between the transverse planes passing through the front and rear ends of said openings, and the longitudinal dimension of the breech-block elements is much smaller.

Furthermore, instead of providing pivoting means for interconnecting the front ends of the breech-block elements, these elements are, according to my invention, merely applied against each other along vertical edges, which greatly simplifies the firearm.

2

Furthermore, the pivot axis about which said two breech-block elements can rotate with respect to each other may be located exactly at the point where the two front edges of these two elements are in contact with each other; thus, when the breech-block elements are locked in their front position, the area of contact with the rear face of the cartridge case corresponds to a full circle.

Finally, since the breech-block elements are not directly fixed to each other, they can undergo small individual displacements when they bear against the corresponding abutment shoulder of the breech-case, which ensures an equal distribution of the stresses between the two breech-block elements.

15 Preferred embodiments of my invention will be herein-after described with reference to the accompanying drawings, given merely by way of example and in which:

10 Figs. 1 and 2 show, with some parts removed, respectively in elevation with portions in section on the line I—I of Fig. 2 and in plan view with portions in section on the line II—II of Fig. 1, the breech mechanism of an automatic cannon made according to my invention.

20 Fig. 3 is a plan view, on a smaller scale and partly in section through the horizontal axial plane of the barrel, of the sliding system of this mechanism.

25 Fig. 4 is a perspective view, with portions cut away, of said breech mechanism.

30 Fig. 5 shows a modification of some parts of this mechanism.

The following detailed description relates to the construction of a small bore automatic cannon.

The firearm includes a barrel 1, preferably removable, extending rearwardly to form a breech case 2.

35 This barrel and breech case unit has a longitudinal (generally vertical) plane of symmetry. Its walls transverse to said plane, i. e. in the conventional arrangement its top and bottom walls are provided with openings, one of these openings serving to the introduction of fresh cartridges and the other to the ejection of spent cartridge cases.

40 The breech mechanism includes two breech-block elements 3a and 3b capable of moving transversely between a retracted and unlocked position (shown by Figs. 3 and 5) in which they can reciprocate inside breech case 2, and an active locked position (shown by Figs. 2 and 4) in which they bear upon said breech case, against distinct abutment shoulders 4 made of an especially hard metal, the front edges of said breech-block elements then constituting the bearing surface which temporarily closes the 45 firearm cartridge chamber behind the rear wall 5a of the cartridge case 5 in firing position.

45 Shoulders 4 are located in a portion of breech case 2 intermediate between the transverse planes passing through the front and rear ends of the two above mentioned openings.

50 A sliding unit 6 supports both a striker 7 and the above mentioned breech-block elements 3a and 3b, which are slidable on said unit 6. This unit 6, which is urged forwardly by return means which will be more explicitly referred to hereinafter, is adapted to have, once said breech-block elements 3a and 3b have reached the end of their forward stroke, a supplementary forward displacement intended first to bring said breech-block elements into locked position and to hold them 55 therein, and finally to fire the cartridge.

55 Breech-block elements 3a and 3b are constituted by two similar pieces mounted symmetrically with respect to the longitudinal plane of symmetry of the firearm and having front edge lines held adjacent to each other along a vertical line XX', the movements of said elements from their retracted unlocked position to their expanded locked position and vice versa being obtained by horizontal

pivoting thereof about vertical line XX' (of course the terms "horizontal" and "vertical" are used on the assumption that the arm barrel is horizontal and its longitudinal plane of symmetry is vertical).

Sliding unit 6 is arranged to act, in the course of its supplementary forward stroke, as a wedge between said elements 3a and 3b so as to cause them to pivot about line XX' until they bear against abutments 4.

The inner walls of breech-block elements 3a and 3b form, opposite block 6, recesses leaving between said elements a space C the horizontal section of which decreases gradually toward the front, as clearly shown on Fig. 2 for member 3a and on Fig. 3 for member 3b.

The sliding unit is constituted by two bars 6a guided longitudinally in slideways 2a provided for this purpose in the breech case, said sliding bars being interconnected by a cross piece 6b which carries the block 6 which forms the active element (with respect to elements 3a and 3b) of said sliding unit.

Block 6 is provided with vertical shoulders S inclined outwardly toward the rear and adapted to bear, as long as elements 3a and 3b are in retracted position, against surfaces s of corresponding inclination carried by said elements, the supplementary forward stroke of the sliding unit producing, through a cam effect exerted by shoulders S on surfaces s, the outward transverse pivoting of elements 3a and 3b which have then reached the end of their forward stroke and have thus been brought into active position (the position of the respective parts when shoulders S start acting on surfaces s is shown by Fig. 3 and the position of the same parts once locking has been preformed is shown by Fig. 2).

The sliding unit carries, on the one hand, near the rear end thereof and preferably on block 6 proper, trigger stops 6c and, on the other hand, near the front end thereof and preferably on cross plate 6b, two projections 6d (shown on Fig. 4) which determine the limit forward position of elements 3a and 3b with respect to unit 6 during the recoil of the reciprocating breech parts and imperatively compel said elements 3a and 3b to move toward each other at the beginning of the recoil stroke of the sliding unit.

I further provide, in the central region of the front edges of said elements 3a and 3b, a passage for the point of striker 7.

It should be noted that I might also, according to a modification illustrated by Fig. 5, substitute for shoulders S rollers 8 cooperating with the surfaces s of elements 3a and 3b.

Anyway, the semi-circular portions Ta and Tb of the front faces of elements 3a and 3b, which are to constitute the bearing surface for the rear wall 5a of the cartridge 5 when said elements are in front position, must be located in the same plane when the breech-block elements occupy their locked position, whereby said cartridge rear wall is then supported over its whole area (position shown for member 3a on Fig. 2). Surfaces Ta and Tb will therefore form a dihedral angle when elements 3a and 3b are retracted, as shown by Fig. 3.

On the other hand, due to the fact that elements 3a and 3b are still retracted when they must, by means of their front edges, push a fresh cartridge into the cartridge chamber, it is of interest to provide said front edges, above semi-circular surfaces Ta and Tb, with plane surfaces t_a and t_b the planes of which form, with those of said surfaces Ta and Tb, an angle such that said surfaces t_a and t_b are located in the same plane when elements 3a and 3b are retracted, and can thus bear through their whole area against the rear wall on the fresh cartridge to be fed (position shown by Fig. 3).

This firearm is further provided on the one hand with an extractor 9 mounted, as will be more explicitly explained hereinafter, in cross piece fashion between elements 3a and 3b and, on the other hand, with a control device capable of producing after the firing of every

round, a recoil displacement of the sliding unit against the action of a recuperator system intended to achieve the forward return movement of said sliding unit.

Concerning first extractor 9, it is arranged in such manner that its nose 9a projects to the front of the front edge of elements 3a and 3b and to the inside of the periphery of bearing surfaces Ta-Tb.

Extractor 9 includes a transverse trunnion 9b the journal portions of which engage in housings 10 provided for this purpose in elements 3a and 3b.

These journals and housings are arranged in such manner as to make allowance for the pivoting movements of elements 3a and 3b, for which purpose, for instance, and as shown by Fig. 5, the journal surfaces of the trunnion are made of straight cylindrical shape over their whole length and housings 10 are given a flaring shape (from their orifice toward their bottom) whereby the journals of the trunnion bear against the front portion of housings 10 when elements 3a-3b are retracted toward each other and against their rear portion when these elements are moved away from each other.

In order to keep said extractor in a position such that it can grasp the rear part of the cartridge case, I provide two springs 11 housed in longitudinal bores formed for

this purpose respectively in each of the elements 3a and 3b, said springs further tending, due to the fact that their lines of action are oblique with respect to axis XX', to move said elements 3a and 3b away from each other.

It should be noted that the trunnion also has the function of keeping the two elements 3a and 3b exactly opposite each other, with their vertical edge lines in contact along XX'.

Concerning now the device for operating sliding unit 6, it is preferably of the type acting by tapping of gas from the firearm barrel.

Although this control device may be made in the usual manner, that is to say include a driving piston acting upon the sliding unit through a fork and push-pieces housed in the breech case, it seems preferable to arrange

40 said control device according to a particular feature of my invention, applicable to all firearms having a sliding unit intended temporarily to keep the breech mechanism in locked position.

According to this feature, I convey, through a system of 45 conduits 12, the gases tapped from the firearm barrel toward two chambers of variable volume 13, of quadrangular section, provided in the breech case and the movable wall of which is constituted by the front edge of sliding bars 6a, said chambers 13 being consequently located near 50 the front of the breech case in line with the sliding bars 6a of sliding unit 6.

Concerning the recuperator system which is to return said sliding unit forwardly, it is preferably made, according to another feature of my invention, independent 55 of the preceding ones, in such manner that it cooperates with the unit in question not directly but through an intermediate part having a movement simultaneous with that of the sliding unit but of smaller amplitude, whereby it is possible to reduce the overall dimensions of the 60 firearm.

For this purpose, as shown by the drawings, I provide each sliding bar 6a with a rack 14 meshing with a pinion 15 carried by a sliding member 16, preferably of cylindrical shape, movable in a longitudinal bore provided 65 for this purpose in the breech case, said pinion 15 rolling on a fixed rack 17 carried by said breech case.

Each sliding member 16, the displacements of which are of an amplitude equal to one half of that of sliding unit 6, cooperates with a return spring 18 housed in the 70 guiding bore of the sliding member.

It should be noted that it will be further of interest to provide, in the usual manner, near the rear of the firearm, an accelerator elastic system (not shown) capable of reinforcing the action of springs 18 by giving sliding unit 75

6, when it comes near the end of its rearward stroke, a forward impulse.

This automatic cannon works as follows:

The sliding unit, which is supposed to start from its extreme rear position (the triggers being depressed) is moved forwardly by return springs 18, elements 3a and 3b being then located in the retracted position shown by Fig. 3.

In the course of this movement, the surfaces t_a and t_b of the front edges of said elements (which surfaces are then located in the same plane) push against the rear part of the cartridge to be fed and introduce said cartridge into the cartridge chamber at the end of their forward stroke.

Once elements 3a and 3b have reached their limit forward positions, sliding unit 6 starts on its supplementary forward displacement, shoulders 5 pushing said elements 3a and 3b into locked position (as shown by Fig. 2) and finally, striker 7 strikes the rear part 5a of the cartridge already housed in the cartridge chamber, thus firing the shot. During the whole of the supplementary stroke of sliding unit 6, subsequent to the bringing of elements 3a and 3b into active position, said unit opposes any unlocking of said elements.

The gases tapped from the arm barrel then act directly upon the front edges of sliding bars 6a and cause the sliding unit to recoil and, when it has moved rearwardly a sufficient distance, this unit ceases to hold elements 3a and 3b. Due to the fact that the slope angle of abutment 4 is reversible, the thrust exerted by the cartridge case, in combination with the action of projections 6d, compels elements 3a and 3b to retract toward each other and then to slide rearwardly together with the sliding unit. In the course of this recoil movement, the extractor catches the spent cartridge case which is expelled through the action of a mechanism not shown by the drawing. When the recoil movement is finished and supposing that the triggers have not been released, the whole of the sliding unit 6 and elements 3a and 3b starts back in the forward direction under the combined actions of the accelerator system and return springs 16. The same cycle of operations is then repeated.

The chief advantages of my system are its simplicity, its light weight and its performance, especially concerning the rate of fire.

These advantages result in particular, as already above explained, from the fact that the conventional heavy breech-block is replaced by light elements which are locked directly on the breech case, from the small length of these elements and from the direct pneumatic control of the sliding unit.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

The present application is a division of my U. S. application Ser. No. 218,370, filed March 30, 1951, now Patent No. 2,756,640.

What I claim is:

1. A self-loading firearm which comprises, in combination, a barrel including a cartridge chamber, a breech case at the rear of said barrel, said barrel and said breech case having a longitudinal plane of symmetry, said breech case being provided, in the two walls thereof perpendicular to said plane of symmetry, with two openings respec-

tively, one for introduction of fresh cartridges and the other for ejection of spent cartridge cases, a sliding unit including two longitudinal side bars longitudinally guided in said breech-case between said openings and a cross plate extending between said bars, said sliding unit being reciprocable longitudinally in said breech case with a given stroke, two breech-block elements symmetrical with respect to said longitudinal plane of symmetry and longitudinally guided with a limited relative displacement with respect to said unit, said relative displacement being smaller than said stroke whereby said breech-block elements are reciprocable longitudinally with respect to said breech case, two locking abutments carried by the inner walls of said breech case located on opposite sides of said plane of symmetry, said abutments being located in a transverse plane located between the front and rear ends of said openings, the rear edges of said breech-block elements being shaped to cooperate with said locking abutments respectively to be locked in cartridge chamber closing or active position, said two breech-block elements adjoining each other at the front along a line at right angles to the axis of said barrel and located in said longitudinal plane of symmetry and being pivotable with respect to said sliding unit in opposite directions about said line, so as to be able, at the end of their forward stroke, to have their rear edges engaged with said locking abutments, a block rigid with said cross plate including shoulders arranged to engage in wedge-like fashion between said breech-block elements for pivoting them outwardly into cooperating engagement with said locking abutments and to hold them thus engaged during the supplementary forward displacement of said sliding unit made possible by its limited longitudinal sliding relation with said breech-block elements, means operative by the firing of each round for imparting a rearward impulse to said sliding unit and elastic means for urging said sliding unit forwardly after each rearward stroke thereof.

2. A firearm according to claim 1 in which said sliding unit carries, near the front end thereof and on its cross plate, two projections arranged to determine the limit forward position of the breech-block elements with respect to the sliding unit and imperatively to compel them to move toward each other at the beginning of the recoil stroke of the sliding unit.

3. A firearm according to claim 1 including semi-circular surfaces on the front edges of said breech-block elements to bear against the rear wall of a cartridge in the cartridge chamber when said elements are in active position, said semi-circular surfaces being located in the same plane when these elements are in locked position.

4. A firearm according to claim 1 including semi-circular surfaces on the front edges of said breech-block elements to bear against the rear wall of a cartridge in the cartridge chamber when said elements are in active position, said semi-circular surfaces being located in the same plane when these elements are in locked position, the front edges of said breech-block elements being further provided, above said semi-circular surfaces, with flat surfaces oblique with respect to said semi-circular surfaces so as to be located in the same plane when the breech-block elements are retracted.
